United States Patent Office

Des. 197,736
Patented Mar. 17, 1964

197,736

SPECTACLE CASE OR SIMILAR ARTICLE

Harry A. Tawil, 977 E. 7th St., Brooklyn, N.Y.

Filed July 9, 1963, Ser. No. 75,716

Term of patent 14 years

(Cl. D57—1)

I claim:

The ornamental design for a spectacle case or similar article, substantially as shown.
